UNITED STATES PATENT OFFICE

WILHELM DÜTZMANN, OF NEUSTADT, GERMANY

HORIZONTAL ALKALI-CELLULOSE PRESS

Application filed April 17, 1930, Serial No. 445,105, and in Germany November 4, 1929.

The present invention relates to a horizontal dipping press, more particularly adapted for the manufacture of artificial silk, which is characterized by its predominating simplicity in mechanical construction and by low cost of manufacture.

In the known presses of a similar character the dipping container extends to the thrust bearing and the rear wall of the dipping container resting against this is replaced or closed and packed, a wall (slide) movable vertically up and down, which is supported by the thrust bearing. If the movable rear wall of the dipping container is removed (raised) the contents of the container (viz. the cellulose and the sheet metal plates and partitions supporting the cellulose between them) may be removed rearwardly through the suitably apertured thrust bearing in the 10 longitudinal direction of the container. By reason of this movable rear wall of the dipping container considerable difficulties are met with in closing the latter in a fluid tight manner. The partitions when moved out of 15 the container and outside the latter are also insufficiently guided. In comparison therewith there are obtained the advantages above referred to by extending the dipping trough as a whole through a distance suitable for the ejection of the treated sheets of cellulose from the dipping container and at 20 the point at which the extension of the dipping trough commences an aperture (fall opening) is provided in the bottom of the 25 container adapted to be closed in a fluid tight manner by suitable members such as slides flaps or the like, whilst the thrust bearing is arranged on the rear wall of the extended dipping container or directly behind the fall 30 opening and in the latter case the dipping container is passed through the thrust bearing which is apertured in the known manner.

For the purpose of explaining the invention two examples of construction are illustrated in the accompanying drawings wherein:

Fig. 1 is a longitudinal section of the parts of the dipping trough under consideration.

Fig. 2 is a section on the line 2—2 of Fig. 1 looking in the direction of the arrow α .

Fig. 3 is a plan of Fig. 1.

Fig. 4 is a sectional view partly in elevation, illustrating a further form of the invention.

Fig. 5 is a corresponding plan.

The dipping container a is according to the invention extended through the frame and in comparison with previous constructions by the portion a^1 so that the rear wall a^2 of the container is no longer in front (as regards Fig. 1) but behind the thrust bearing. The trough is provided in the known manner with four guide rails c with which engage the partitions d between which the cellulose sheets (not shown) are supported and guided. These guide rails extend without interruption to the rear wall a^2 of the dipping container. At some distance from the rear wall a^2 and in front of the apertured thrust bearing b the bottom a^1 is provided with an aperture a^4 and above this aperture is a suitably strong supporting plate e , arranged to be moved vertically up and down by means of a liquid cylinder f and a pulling member f^1 engaging with its wedge shaped foot e^1 in a correspondingly shaped frame member g in a fluid tight manner, the latter being secured in a fluid tight manner to the bottom a^1 of the dipping container, underneath the fall opening a^4 and bearing against the foot of the thrust bearing b . e^2 is a rubber packing. This may also be provided on a closure member separate from the foot e^1 of the slide e , which member closes the supporting frame g in a fluid tight manner from underneath. As will be seen in Fig. 3, the movable thrust bearing e is only made wide enough to enable the guide rails c to extend to the rear wall a^1 of the dipping container a without interruption.

The press is operated in the manner that with the partitions in the position shown in Fig. 1 the cellulose sheets are inserted and the trough closed at its fall opening by the supporting plate e . Through the tubular member h lye can be now admitted and the chemical treatment and soaking of the cellulose sheets carried out. When this has been done the lye is allowed to flow out through the member i and the pressure head is ad-

vanced by the hydraulic press until the pressing out of the sheets has been effected. The latter by reason of the heavy pressure plate *e* are now directly supported against the thrust bearing *b*. When the pressure plate *e* is removed and the pressure head *k* advanced further the partitions pass into the extension portion *a*¹ of the dipping trough whilst the treated cellulose sheets fall through the fall opening *a*⁴ and the bottom opening *m* downwardly into a truck provided underneath. When all the partitions are in the extension *a*¹ the trough is empty and by retracting the pressure head *k* it is possible, as the partitions *d* are connected together by four chains *n* and to the part *k* to return them into the position shown in Fig. 1.

In the construction shown in Figs. 4 and 5 the thrust bearing *b*, which in the known manner is not apertured, is located behind the rear wall *a*² of the extended dipping container and at a suitable distance from the rear wall *a*² there is provided the fall opening closed by a flap *p*, the latter being capable of being closed in a fluid tight manner against the fall opening or opened downwardly by a weighted link mechanism *q*. In this form of construction after allowing the lye to flow out the partitions are first moved against the rear wall *a*² together with the cellulose sheets and the pressing takes place in this position. The pressure head is then again retracted when, with the flap *p* open, the cellulose sheets fall out, whilst the partitions *d*, guided by the rails *c*, again return to their initial position when the press can again be charged. The construction of the fall opening *a*⁴ and of the corresponding closing means and the actuation thereof may be modified according to the particular requirements without departing from the scope of the invention.

What I claim is:

1. In a horizontal alkali-cellulose press in combination with a dipping trough, having an exit opening and a thrust bearing, arranged behind the exit opening, a supporting plate, having its bearing at the thrust bearing, a closing member for closing the exit opening and being directly attached to the supporting plate, and means for moving the supporting plate up and down, together with the closing member.
2. In a horizontal alkali-cellulose press including a dipping trough formed with an exit opening, a thrust bearing for the trough arranged immediately adjacent the exit opening, and means for selectively closing said exit opening, said means serving as a limit for the pressing operations and held against movement under such pressing operations by the thrust bearing.
3. In a horizontal alkali-cellulose press, a dipping trough formed with an exit opening, a plurality of material-receiving partitions in said trough, means for exerting pressure on

the partitions, and a vertically movable member serving to form an abutment for the pressure movement of the said partitions and selectively serving as a closure for the exit opening.

4. In an alkali-cellulose press, a dipping trough formed with an exit opening for the material, a plurality of pressing partitions arranged in the trough, between which the material is received, means operative in the trough for exerting pressure on said partitions and material included therebetween, means in the trough for guiding the partitions, and an element serving to selectively close said exit opening, said element extending transverse the trough within the partition guiding means to provide an abutment for the pressure limit movement of the partitions.

In testimony whereof I affix my signature.

WILHELM DÜTZMANN.
